UNITED STATES PATENT OFFICE

2,366,644

SIFTER CLOSURE

Robert Nyden, Manhasset, N. Y., assignor to F. N. Burt Company, Inc., Buffalo, N. Y., a corporation of Delaware

Application December 4, 1942, Serial No. 467,853

8 Claims. (Cl. 222—555)

This invention relates to improvements in containers and more particularly to improvements in closures of the dispensing or sifter type adapted for dispensing free flowing material, such as toilet or other powders. The improved closure has been particularly designed so that it may be conveniently constructed entirely of non-metallic materials, thus to conserve metallic materials that are vitally needed at this time for national defense. At the same time a high degree of anti-sift properties have been maintained. The closure has been especially designed, furthermore, so as to be capable of production in large quantities by factory methods at low cost. Thus the improved closure, together with the entire container, is especially designed so as to be constructed of fibrous materials, such as, cardboard, fiberboard, pulp, wood, or from the various plastic materials.

It is a general object of the invention to provide a closure of the class mentioned that can be made of non-metallic materials, quickly and easily assembled in manufacture, and at the same time provide a tight anti-sift joint that is readily adjustable to maintain tightness so as to prevent escape or sifting of the container contents when the closure is in closed position.

A further object of the invention is to provide an improved adjustable friction holding device for holding the closure parts in tight closing position, and embodying a friction dowel or dowel pin frictionally engaging in an aperture in the top or cap of the container, thus making it easy to maintain the closure elements in tight anti-sift condition during long periods of usage, while at the same time providing for easy operation of the closure member into closing or opening positions and for holding it there.

Still another object of the invention is to provide an improved closure of the class mentioned adapted for economical manufacture by factory methods in large quantity production, wholly from non-metallic materials and at the same time assuring a practical closure that is easily handled and operated and capable of maintaining non-leak qualities over long periods of use.

Other objects of the invention are in part pointed out below in connection with the detailed description of certain illustrative embodiments, and will be in part obvious in connection therewith.

The invention accordingly comprises the features of construction, combination of elements, and arrangement of parts, which will be exemplified in the construction hereinafter set forth and

the scope of the application of which will be indicated in the claims.

For a more complete disclosure of the nature, objects and advantages of the invention, reference is had to the following detailed description of an illustrative but preferred embodiment of the invention, and to the accompanying drawing in which:

Fig. 1 is a side elevation of a can or container 5 for toilet powder or similar materials and embodying the invention;

Fig. 2 is a top plan view thereof;

Fig. 3 is an enlarged vertical section taken substantially on the line 3—3 of Fig. 2, the closure being shown partially diagrammatically for clearness;

Fig. 4 is a plan view similar to Fig. 2 but showing a slightly modified embodiment.

Referring to the drawing for a detailed description of the illustrative embodiments of the invention there shown, the container or powder can 5 may be of any desired size and shape but is preferably constructed of non-metallic material, such as paper, cardboard, fiberboard, and the like, and has an interior compartment for receiving the powder or other material. The container has an opening at its upper end which is closed by a head or upper wall 6 having a downwardly extending circumferential attaching flange 7 adapted to fit tightly within the upper walls of the container 5. The head or cap 6 is preferably formed with an outer circumferential flange 8 forming a seat against which the upper end of the container wall 5 rests. At its outer surface the attaching flange 7 is preferably formed with a circumferential bead 9 extending entirely around the flange and engaging the inner surface of the container wall 5. This bead 9 is so constructed and arranged as to extend or bite slightly into the inner wall surface, thus holding the head in assembled relation and at the same time making a tight anti-sift joint. By means of this arrangement the head 6 is easily assembled with the body 5 of the container so as to make a permanent tight joint. It is obvious that a different attaching means may be provided for the head 6, and, if desired, the head may be made as an integral part of the body of the container 5.

In the embodiment shown in the drawing the container closure is assembled upon the container head 6 which is preferably made of wood, fiberboard, plastic material, or other non-metallic material. The head 6 is formed with an upper thickened portion 10 finished to form an upper flat sup-

porting surface or seat for the closure member hereafter fully described. This thickened portion or wall 10 is formed with one or more dispensing openings or passageways 11 extending vertically through the wall to the interior of the container. This thickened wall 10 is also formed with a centrally disposed retaining opening 12 extending vertically through the wall and preferably of a diameter ordinarily considerably larger than that of the dispensing openings 11. This retaining opening 12 presents a smooth inner frictional surface for a purpose later fully described.

A closure member or plate 13 rests upon and is supported by the upper surface or seat of the thickened wall 10. This closure member is provided with one or more dispensing openings 14. In the embodiment of Figs. 1, 2 and 3 there are several spaced dispensing openings 11 in the head 6 and a corresponding number of equally spaced openings 14 in the closure member 13. In the embodiment shown, the closure member 13 is in the form of a flat rotary disk having a flat lower surface conforming to that of the seat of the head 6. The closure member also has a centrally disposed retaining opening for rotatably mounting and retaining the disk in operative position on the container head. The outer peripheral edge of the closure disk extends into exposed position so as to provide a serrated operating marginal portion 15 adapted to be engaged by the user for rotating the disk to open and close the container.

Overlying the rotary closure member 13 is a retaining member or plate 16 which in the embodiment disclosed is in the form of a flat disk of slightly less diameter than that of the closure disk 13. Preferably as shown, this retaining disk is of sufficient diameter to extend outwardly beyond the dispensing openings 11 and is itself provided with dispensing openings 17 positioned and spaced for alignment with the respective dispensing openings 11 and 14. If the retaining disk 16 is of smaller diameter so that the outer edges thereof terminate at or inside the dispensing openings 11 and 14, as is sometimes desirable, in such case, the dispensing openings 17 will not be needed.

The retaining disk 16 is adapted to hold the closure disk 13 at all times tightly against the seat at the upper surface of the head 6 so as to form a tight anti-sift joint for the dispensing openings 11 when the closure disk is rotated into closing position, as shown in Fig. 2. In order to maintain this tight anti-sift relation at all times, an adjustable friction attaching device is provided. In the embodiment shown this friction attaching device embodies the dowel or dowel pin 18 attached to and extending downwardly from the inner surface of the retaining disk 16. Although this dowel pin may be made integral with the retaining disk 16, if desired, it is preferably made as a separate part, as shown, and is attached to the under surface of the retaining disk by an appropriate attaching means. It is convenient to form the dowel pin with a flat upper surface and to attach it to the under surface of the retaining disk by adhesive means shown diagrammatically at 19. The dowel pin 18 may be constructed of wood, laminated cardboard, or fiberboard, or other similar material and is made of a diameter to fit snugly within the central retaining opening 12 of the thickened wall 10. The dowel, as shown, may be circular in horizontal section, or it may be made of other configuration such as square or polygonal. It is of sufficient length to extend through the rotary closure disk 75

13 and substantially through the thickened wall 10 having a flat inner end surface. As it is also of considerable diameter, as shown, it thus has a sufficiently large peripheral surface whereby it functions to frictionally engage with the inner frictional surface presented by the retaining aperture 12 to retain the parts securely in assembled relation. Since the dowel pin extends through the central retaining opening of the rotary closure disk 13, it serves as a pivotal support upon which the closure disk rotates. The rotary closure disk is sufficiently loose upon the pivotal support or dowel 18 to permit free rotary movement of the disk into opening and closing positions.

In the disclosure of Fig. 3 it will be understood that the closure elements are shown partially diagrammatically as being separated slightly in order that the construction and arrangement may be seen more clearly. When the parts are in operative position the rotary disk rests snugly against the upper seat of the wall 10 and the retaining disk 16 rests snugly against the upper surface of the closure disk. Therefore, the closure disk 13 is retained frictionally in its open or closed position by engagement with the head and the retaining member 16.

In the embodiment of Fig. 4 the structure is similar to that of the embodiment above described and corresponding parts are indicated by the same reference numerals. However, in this embodiment the retaining disk 16 has but a single dispensing opening 20 and the head or wall 6 of the container is provided with a similar aligning dispensing opening. The rotary closure disk 13 in this case is formed with two diametrically opposed dispensing openings 21 corresponding to and functioning similarly to the dispensing openings 14 of the embodiment previously described.

From the foregoing disclosure, it will be seen that the rotary closure disk 13 of the different embodiments can be maintained at all times in close sift-tight relationship with the dispensing openings of the head 6 by the very simple adjustable friction holding device provided by the dowel 18. In case at any time there becomes a slight looseness between the rotary closure member 13 and the container head due to wear, to shrinkage, or to any other cause, this may be quickly and easily remedied by merely pressing upon the outer surface of the retaining disk 16 opposite to the dowel pin so as to force the latter a little further into the retaining socket or aperture 12 of the head. The dowel pin together with the retaining disk and the rotary disk are maintained in this adjusted tight position by means of the frictional engagement between the pin and the friction surface of the retaining opening. Also, the parts can be quickly and easily assembled at the factory merely by placing the closure disk in its operative position and inserting the dowel pin with the retaining disk into position in the retaining aperture 12. The parts are held together by the frictional attachment, no additional attaching means being required. When the parts are being assembled the dispensing apertures of the retaining disk 16 are adjusted to align respectively with the dispensing apertures of the head 6. The dispensing apertures 14 of the rotary closure disk are sufficiently spaced apart so that the dispensing apertures of the head and retaining disk are completely closed when the closure disk is sufficiently rotated.

Reference is made to applicant's prior application, Serial No. 450,277, filed July 9, 1942 and since issued as Patent Number 2,336,882, over

which the present invention is an improvement.

Since certain changes may be made in the above construction and different embodiments of the invention could be made without departing from the scope thereof, it is intended that all matter contained in the above description or shown in the accompanying drawing shall be interpreted as illustrative and not in a limiting sense.

Having described my invention, what I claim as new and desire to secure by Letters Patent is:

1. In a container closure, in combination, a container wall or head having a retaining opening with a friction surface and having one or more dispensing openings, a closure member mounted for movement into opening or closing positions with reference to said dispensing opening, and a retaining member for said movable closure member having an attaching extension forming a friction dowel pin frictionally engaging said friction surface of said retaining opening, said friction surface and said dowel pin being relatively shaped and proportioned so as to frictionally engage in holding relation in different relative longitudinal adjustments of said dowel pin to provide an adjustable friction holding device for adjusting the degree of tightness of said closure member.

2. In a container closure, in combination, a container wall or head member having one or more dispensing openings, a closure mounted for movement into opening or closing positions with reference to said dispensing opening, a retaining member for said movable closure, one of said members having a retaining opening with a friction retaining surface and the other said member having an attaching extension forming a friction dowel pin projecting from one side thereof, said dowel pin having an outer friction surface frictionally engaging said friction surface of said retaining opening, said friction retaining surface and said dowel pin being relatively shaped and proportioned so as to frictionally engage in holding relation in different relative longitudinal adjustments of said dowel pin to provide an adjustable friction holding device for adjusting the degree of tightness of said closure member.

3. In a container, in combination, a container wall or head having a dispensing opening and having a surface forming a closure member seat, a closure member mounted on said seat so as to make a tight joint therewith and movable into opening or closing positions with reference to said dispensing opening, a retaining member overlying said closure member so as to hold the latter against said seat, and a friction dowel pin connected to said retaining member and frictionally held in different relative longitudinal adjustments thereof to form an adjustable friction holding device for adjusting the degree of tightness of said closure member.

4. In a container, in combination, a head or wall member having a surface forming a closure seat and having a dispensing opening, a closure mounted on said seat so as to make a tight joint therewith and movable into opening or closing positions with reference to said dispensing opening, a retaining member for said closure to hold the latter against said seat, one of said members having a retaining opening with a friction retaining surface, and a dowel mounted upon the other of said members and projecting from one side thereof and extending into said retaining opening, said dowel having an outer friction surface frictionally engaging the friction surface of said retaining opening, said friction surfaces being

5 relatively shaped and proportioned so as to frictionally engage in holding relation in different relative longitudinal adjustments of said dowel to form an adjustable friction holding device for adjusting the degree of tightness of said closure member.

5. In a container, in combination, a container head or wall member having a surface forming a closure seat, said wall member having a dispensing opening, a rotary closure disk mounted on said seat so as to make a tight joint therewith and movable into opening or closing positions with reference to said dispensing opening, said closure disk having a retaining opening and having a dispensing opening adapted to register with said dispensing opening of said head, a retaining member for said closure disk to hold the latter against said seat, one of said members having a retaining opening with a friction retaining surface, and a dowel mounted upon the other of said members and projecting into said retaining opening, and extending through the retaining opening of said closure disk to rotatably mount the same, said dowel having an outer friction surface frictionally engaging the friction walls of said retaining opening, said friction surface and friction walls being relatively shaped and proportioned so as to frictionally engage in holding relation in different relative longitudinal adjustments of said dowel to provide an adjustable friction holding device for adjusting the degree of tightness of said closure member.

6. In a container, in combination, a container wall or head having a surface forming a closure member seat, said wall or head having a dispensing opening and having also a retaining opening with an interior friction surface, a rotary closure disk mounted on said seat so as to make a tight joint therewith and movable into opening or closing positions with reference to said dispensing opening, said closure disk having a retaining opening and having a dispensing opening adapted to register with said dispensing opening of said wall or head, a retaining disk overlying said closure disk so as to hold the latter against said seat, an outer marginal portion of said retaining disk extending outwardly beyond the dispensing opening of said closure disk and having a dispensing opening adapted to register with the dispensing openings of the head and closure disk, and a dowel mounted upon and projecting inwardly from one side of said retaining disk and extending into said retaining openings of said wall or head and rotary disk and rotatably mounting the latter, said dowel having an outer friction surface frictionally engaging the friction surface of said retaining opening of said head, said friction surfaces being relatively shaped and proportioned so as to frictionally engage in holding relation in different relative longitudinal adjustments of said dowel to provide an adjustable friction holding device for adjusting the degree of tightness of said closure member.

7. In a container closure, in combination, a container wall or head having a retaining opening with a friction surface and having one or more dispensing openings, a closure member mounted for movement into opening or closing positions with reference to said dispensing opening, a retaining disk for said movable closure member, a friction dowel pin adhesively attached to said retaining disk and extending from one side of the latter and frictionally engaging said friction surface of said retaining opening, said friction surface and said friction dowel pin being

relatively shaped and proportioned so as to frictionally engage in holding relation in different relative longitudinal adjustments of said dowel pin to provide an adjustable friction holding device frictionally held in different adjusted positions for adjusting the degree of tightness of said movable closure member in its operative position.

8. In a container, in combination, a container wall or head member having a dispensing opening and having a closure member seat, a closure member mounted on said seat and movable thereon into opening and closing positions with reference to said dispensing opening, and a friction retaining device for holding said movable closure mem-

ber on said seat, said friction retaining device having a retaining part in retaining engagement with one of said members, and said friction retaining device having an adjustable friction dowel pin frictionally engaging in an opening in a part of one of said members, said last mentioned opening and said dowel pin being relatively shaped and proportioned so as to frictionally engage in holding relation in different relative longitudinal adjustments of said dowel pin to provide an adjustable friction holding device for adjusting the degree of tightness of said movable closure member in its operative position on said seat.

ROBERT NYDEN.
